UNITED STATES PATENT OFFICE.

OLOF N. TEVANDER, OF CHICAGO, ILLINOIS, ASSIGNOR TO STANDARD CAP & SEAL CORPORATION, OF CHICAGO, ILLINOIS, A CORPORATION OF VIRGINIA.

DESIGN FOR A CARTON OR SIMILAR ARTICLE.

Application filed October 23, 1922. Serial No. 4,068. Term of patent 7 years.

To all whom it may concern:

Be it known that I, OLOF N. TEVANDER, a citizen of the United States, residing at Chicago, in the county of Cook and State of Illinois, have invented a new, original, and ornamental Design for Carton or Similar Article, of which the following is a specification, reference being had to the accompanying drawing, forming part thereof.

In the drawing, the figure is a perspective view of the carton, showing my new design.

I claim:

The ornamental design for a carton or similar article, as shown.

OLOF N. TEVANDER.
